UNITED STATES PATENT OFFICE.

WILLIAM W. HUELSTER, OF GRAND RAPIDS, MICHIGAN.

DESIGN FOR AN ANGLE-PLATE FOR FILE-BOXES.

SPECIFICATION forming part of Design No. 32,570, dated April 24, 1900.

Application filed March 30, 1900. Serial No. 10,853. Term of patent 14 years.

To all whom it may concern:

Be it known that I, WILLIAM W. HUELSTER, a citizen of the United States, residing at Grand Rapids, in the county of Kent and State of Michigan, have invented and produced a new and original Design for Angle-Plates for File-Boxes, of which the following is a specification, reference being had to the accompanying drawings, forming part thereof.

Figure 1 is a perspective of an angle-plate, showing my new design; and Fig. 2 is a plan view of the same.

As shown in the drawings, the leading or material feature of my design consists of a plate having portions A and A' arranged substantially at right angles to each other and provided with flanges B and C, projecting from the outer edge of each plate and at right angles thereto, and an arm D, projecting from the upper end of the portion A' and substantially in the plane of the portion A.

The portions A and A' of the plate are rectilinear and at right angles to each other at their outer edges and are provided with edges having curved outlines at their inner or ad-

acent sides, as shown. A flange C, projecting from the rectilinear edge of the portion A', extends from the upper end of the said portion downward to near the right angle, where said portions A and A' join, terminating at a recess E in the portion A', and the flange B extends from the right angle, where the portions A and A' join, to about two-thirds of the length of the portion A, where it terminates, and said flange is provided with spurs F. The arm D is curved laterally in serpentine form and turned inward at the end and has curved upper and under edges, as shown.

Having described my invention, what I claim as new, and desire to secure by Letters Patent, is—

The design for an angle-plate for file-boxes, as herein shown and described.

In testimony whereof I affix my signature in presence of two witnesses.

WILLIAM W. HUELSTER.

Witnesses:

PALMER A. JONES,
G. N. SNYDER.
